UNITED STATES PATENT OFFICE.

HENRY C. LEHMAN, OF MIDDLEBURY, INDIANA.

ANCHOR FOR DREDGES.

SPECIFICATION forming part of Letters Patent No. 624,507, dated May 9, 1899.

Application filed February 8, 1899. Serial No. 704,925. (No model.)

To all whom it may concern:

Be it known that I, HENRY C. LEHMAN, a citizen of the United States, residing at Middlebury, in the county of Elkhart and State 5 of Indiana, have invented a new and useful Anchor for Dredges, of which the following is a specification.

My invention relates to anchors for dredges and other excavating machinery which employ a swinging crane or boom to carry an excavator mechanism adapted to deposit the excised material on a spoil-bank at one side of the line of the stream or other excavation.

The chief object of the present improvement is to provide an anchor mechanism of comparatively simple construction in which the barge, scow, or other carrier for the operating mechanisms may be held stationary against swaying due to the lateral swinging 20 of the crane or boom.

A further object of the invention is to provide an improved arrangement of parts, which may be operated with a minimum expenditure of power and be readily adjusted to the grade 25 of the banks and to inequalities in the surface of the ground in order to secure a firm bearing for the anchor-shoe on the bank.

A further object of the invention is to provide an improved type of beam for the anchor-shoe in which the jointed beam members are adapted to be interlocked in firm relation one 30 to the other when the anchor is adjusted for service.

With these ends in view the invention consists in the novel combination of elements and in the construction and arrangement of parts, which will be hereinafter fully described and claimed.

To enable others to understand the invention, I have illustrated the preferred embodiment thereof in the accompanying drawings, forming a part of this specification, and in which—

Figure 1 is a front elevation of a dredger 45 with my anchor mechanism applied thereto. Fig. 2 is a plan view of one part of the anchor mechanism. Fig. 3 is a vertical section through the structure represented by Fig. 2 and on the plane indicated by the dotted line 3 3 of Fig. 2. Fig. 4 is an enlarged detail transverse section through the hinged 50 guide for the slidable shoe-beam, the plane

of the section being indicated by the dotted line 4 4 of Fig. 3. Fig. 5 is a detail perspective view of the shoe, illustrating the universal-joint connection of said shoe with its beam. Fig. 6 is a detail perspective view of the joint which unites the two members of the shoe-beam. Fig. 7 is a modified form of clevis for supporting and guiding the anchor-beam. 60

Like numerals of reference denote like and corresponding parts in each of the several figures of the drawings.

In order that others may understand the present improvement, I have illustrated the same in connection with a familiar type of dredger, the barge or scow of which is indicated by the numeral 10, the swinging boom or crane at 11, and the bucket excavator at 12; but I would have it understood that 70 while my anchor mechanism is well adapted for use in connection with a dredger I do not strictly limit myself to the employment of the anchor mechanism in connection with an excavator apparatus of this character, because 75 I am aware that the anchor mechanism may be used in connection with excavator machinery generally to hold the carrier or frame thereof from vibration or displacement, which may be due to the swinging of a boom or crane. 80

In carrying my invention into practice in connection with a dredger I employ two pairs of vertical posts 13 14, which are erected on opposite sides of the barge and are firmly secured thereto, and these uprights are braced 85 by a cross-beam 15, which extends horizontally across the roof of the barge and is firmly secured to said uprights in any approved way. Each pair of uprights 13 or 14 is provided on the inner opposing faces thereof with metal- 90 wear-plates 19, which are bolted firmly in place to said uprights and are spaced apart to accommodate between said wear-plates the slidable shoe-beam and its pair of guide-plates. 95

The guide-plates 20 21 are disposed between the wear-plates on the uprights, and these guide-plates have short shafts or trunnions 22, which are fitted loosely in suitable openings or bearings provided in the wear-plates 100 and the uprights or posts. The guide-plates are spaced to receive the slidable shoe-beam between themselves, and said plates 20 21 are united by a series of bolts 23 24. The bolts

23 are fastened to the guide-plates near the upper edges thereof, while the other bolts 24 are fastened to the guide-plates at their lower edges to serve as supports or rests for the slideable shoe-beam.

5 The shoe-beam on one side of the barge or scow is indicated by the numeral 16, while a similar beam on the opposite side of the barge or scow is indicated by the numeral 17. These 10 shoe-beams are independent one from the other, and each beam is equipped with an anchor-shoe 18, the construction of which and the hinge-joint between said beam and the shoe will be hereinafter described. Each shoe-beam 15 is slidably fitted between a pair of the guide-plates 20 21, and it is confined therein by the bolts 23 24, and said guide-plates for each beam are mounted pivotally on the pair of vertical points or uprights 13 14. By thus 20 mounting the shoe-beam it is free to slide in an endwise direction through the guide-plates, and the guide-plates form a hinge or pivotal connection between the fixed posts and the slideable beam, whereby the beam may assume 25 different angular positions with relation to the vertical post and the barge, and thus accommodate itself to the grade of the bank upon which its anchor-shoe 18 is designed to rest.

30 Each shoe-beam 16 or 17 is provided with a pair of holding-plates 25, which extend longitudinally of the beam for a proper distance and are secured firmly to opposite faces of the beam by the bolts 26. The plates 25 are parallel to each other and have their upper edges 35 extended above the top face of the beam. In these extended upper edges of the plates are formed a plurality of notches, which produce the series of coincident teeth 27, and these 40 teeth have rounded working edges and beveled neutral edges, (indicated at 28,) such beveled edges insuring the free outward movement of the shoe-beam with relation to the locking-bail or clevis 29. This locking-bail 45 is pivoted at 29^a in the wear-plates 19, which are fixed to the pair of vertical posts, so that the locking-bail is adapted to drop into engagement with the rounded edges of the teeth 27 on the plates 25 of the shoe-beam to sustain 50 the inward thrust of the shoe-beam and prevent the inward movement of said beam when the anchor is in service. This locking-bail or clevis is provided with a weighted arm 30, arranged to normally press the bail in engagement with the teeth 27 of the beam-plates 25, and said bail may be lifted from engagement with the teeth by permitting the weighted end of the arm 30 to rest on the cross-sill 15 when the shoe-beams are raised, whereby 55 the cant of the weighted arm 30 is arrested by the beam and the locking-bails are disengaged automatically from the toothed plates of the shoe-beams on the elevation of the latter in order to permit the beams to be drawn 60 inwardly for adjusting the same.

65 Each shoe-beam is made of two sections, which are hinged or jointed flexibly together

to adapt the outer section to adjust itself to the grade of the bank and enable the anchor-shoe to obtain a firm bearing on the bank. 70 The lower or outer section of each shoe-beam 16 or 17 is indicated by the numeral 32, and the two sections of the beam 16 or 17 and 32 are joined together by a hinge, which is indicated in its entirety by the numeral 33. 75 This hinge consists of a pair of plates 34, which are fastened to the beam-sections 16 or 17, another pair of plates 35, bolted to the beam-section 32, and a pivotal bolt 36. The two pairs of plates 34 35 on the two sections 80 of the jointed beam are arranged to overlap each other, and thereby enable the pivotal bolt 36 to pass through the protruding ends of both pairs of plates and to extend through the space at the contiguous ends of the beam-sections. One of the important features of my invention is a novel construction of this hinge, by which the two beam-sections may be interlocked firmly together against any tendency to collapsing when the anchor is 90 adjusted for service, and to this end I provide the hinge-plates 34 with locking-arms 37, which are extended beyond the pivotal bolt 36 and are adapted to bear firmly against the studs 38 on the hinge-plates 35. 95

Each anchor-shoe is preferably constructed of two series of bars 18^a 18^b, which are arranged at right angles to each other and in different horizontal planes to provide a substantial light construction of the shoe and secure an extended bearing-surface without increase in the weight of said shoe. Each shoe is coupled to the free extremity of the lower beam-section 32 by means of a universal hinge-joint, that adapts the shoe to assume 100 different positions relatively to the beam and to obtain a firm bearing or rest on the irregular surface of the bank. The beam-section 32 is provided at its outer extremity with a pair of projecting hinge-plates 39, which are bolted firmly to the beam-section 32, and on the anchor-shoe is provided a transverse hinge-bar 40. This hinge-bar is provided at its middle with a pair of plates 41, which are bolted firmly to said bar 40 and extend upwardly therefrom to overlap the hinge-plates 39, and through these hinge-plates 39 41 passes a hinge-bolt 42, which pivotally connects the two pairs of plates together. The hinge-bar 40 is arranged centrally on the anchor-shoe 110 18, and it is connected loosely thereto by a plurality of staple-shaped bolts 43, which embrace the bar 40 and are secured firmly to the series of bars forming the anchor-shoe. It will be observed that the pivotal bolt 42 and the hinge-bar 40 lie at right angles to each other, and these elements with their coacting parts provide a universal joint between the anchor-shoe and the beam-section 32. This universal joint adapts the anchor-shoe 120 to be turned to different angles or positions for the purpose of securing a firm bearing on the ground, and the jointed beam is pivotally connected with the shoe by the bolt 42 130

to enable the beam-sections to be drawn in line with each other without disturbing the position of the anchor-shoe or displacing it on the ground.

- 5 The outer end of the shoe-beam is connected with the vertical posts 13 or 14, near the lower ends thereof, by horizontal braces 44. The braces are fitted loosely to the hinge-bolt 42, and at their inner ends they are connected 10 adjustably to the pair of posts by a bolt 43^a, which passes through the posts and may be fitted in any one of a series of apertures which are provided in the braces 44 near their inner ends.
- 15 To stay the shoe-beams against lateral vibration due to movement of the scow or barge, and thereby obviate undue strain on the hinge-joints of the beams and the parts which coact therewith, I provide a guide-frame on each side of the barge to slidably receive the shoe-carrying beam 16 or 17. This guide-frame consists of a pair of horizontal timbers 45 and the inclined struts 46. The horizontal timbers are united to the vertical 20 posts 13 14 by the hinge-plates 47, while the inclined struts 46 are fastened firmly to the uprights or posts by bolts, as at 48. The slideable inclined beam is fitted between the struts and the timbers of the guide-frame, and this 25 frame is provided at its outer end with a loose guide pulley or sheave 49. Over this pulley passes an elevating-cable 50, which has one end attached to a clevis 51, loosely connected to the hinged joint 33 between the members 30 of the sectional shoe-beam or to the beam 16 or 17. This elevating-cable extends to and is passed around a sheave 52, which is provided on the barge or scow, and the sheaves for the two cables are situated at or near the 35 bow in the middle of the deck on the barge or scow. A haulage-cable 53 is attached to a clevis 54, which is loosely fitted on the hinge-bolt 36, which connects the plates of the hinge 33, that unites the two members of the shoe-beam, and this haulage-cable is passed on a 40 sheave 55 and is then coiled on a drum 56, which is situated across the deck at or near the middle of the barge, and which drum is operated by engine-power of the barge for 45 the purpose of drawing on the series of cables in order to bring the two members of the shoe-beam into alinement with each other for the purpose of raising the barge or scow and imposing a portion of the weight of the 50 dredger on the anchor beams and shoes. The cables 50 53 from the two anchor-beams are thus guided individually by the sheaves to the single drum 56, and this drum is arranged to operate all of the cables.
- 55 The operation of my apparatus may be described as follows: The dredger having assumed the desired position, the series of cables are slackened, and the anchor-beams and the shoes thereof are allowed to slide end- 55 wise in the pivotal guide-plates and the guide-frames, so that the shoes may be extended or projected a proper distance beyond the sides

of the dredger. These shoes are adapted to rest firmly on the banks of the stream or excavation, and the braces 44 are adjusted to 70 connect the lower ends of the hinged sectional beams 16 17 with the uprights or posts 13 14. The locking-bails or clevises 29 engage with the toothed plates of the anchor-beams to prevent inward movement thereof, 75 and these locking-bails transmit the inward thrust of the anchor-beams to the uprights or posts 13 14. The haulage-cables 53 are now drawn inwardly by the drum 55 for the purpose of bringing the members of the hinged 80 anchor-beams into line with each other, and the movement of each beam-section is limited or arrested by the arms 37 engaging with the studs 38. It will be observed that each anchor-beam has its lower end pivoted to the 85 anchor-shoe, while its upper end is supported by guide-plates, which have pivotal connection with the fixed posts or uprights, whereby the beam-sections are adapted to turn when the cable 53 is drawn taut, and thus 90 permit the beam-sections to assume the alined positions without torsional strain on the parts of the apparatus. The operation of straightening the jointed anchor-beams by the action of the haulage-cables 53 serves to raise the 95 dredge a limited distance—say about a foot—in the water, and a portion of the weight of the dredger is thus imposed on the anchor-beams and the shoes, whereby the dredge is anchored firmly in place against tendency to 100 ward lateral displacement owing to the swinging of the crane or boom when depositing the excised material upon the bank.

In lieu of the pivoted plates and the series of bolts therein to serve as the pivotal support for the slideable inner members of the shoe-beams I may use the pivotal bail 58. (Shown by Fig. 7 of the drawings.) This bail 58 is arranged between the pair of uprights and is pivotally connected thereto, and in the 105 bail rests the inner member of the shoe-beam, so that it may slide in the bail and is held in place thereby for the locking-bail to engage with the notched plates on the shoe-beam.

Changes may be made in the form and proportion of some of the parts, while their essential features are retained and the spirit of the invention embodied. Hence I do not desire to be limited to the precise form of all the parts as shown, reserving the right to 115 vary therefrom.

What I claim is—

1. In an anchor for excavators, the combination with an upright or post, of a jointed anchor-beam slidably confined on said post 120 or upright, a shoe connected to the outer extremity of said jointed beam, means for applying strain to the joint of said sectional beam, and a locking device to sustain the inward thrust of the beam and shoe, substantially as described.

2. In an anchor for excavators, the combination with a post or upright, of a pivotal guide supported thereon, a jointed anchor-

beam slidably confined in said guide, and a locking device to sustain the inward thrust of the anchor-beam, substantially as described.

3. In an anchor for excavators, the combination with a post or upright, of an anchor-beam slidably fitted to said post or upright, and an anchor-shoe united by a universal joint to the outer extremity of the anchor-beam, substantially as described.

10 4. In an anchor for excavators, a jointed sectional anchor-beam having its members joined together by a stop-hinge constructed to limit the movement of the beam members when alined, in combination with a post or 15 upright on which one of the beam members is slidably confined, an anchor-shoe connected to the free extremity of the other beam member, and a haulage-cable connected with the hinged joint between the beam members, 20 for the purpose described, substantially as set forth.

5. In an anchor for excavators, a sectional anchor-beam and a stop-hinge consisting of plates applied to the contiguous ends of the 25 beam members, a pivotal bolt connecting the hinge-plates, and coacting stop devices on the respective hinge-plates to limit the movement of the beam members when alined with each other, in combination with a post or 30 upright on which one beam member is slidably confined, an anchor-shoe connected with the other beam member, a haulage-cable, and a clevis connecting said haulage-cable with the pivotal bolt of the stop-hinge, substantially 35 as described.

6. In an anchor for excavators, the combination with uprights or posts, of connected guide-plates pivotally supported in said posts, an anchor-beam provided with a rack and 40 slidably fitted within said connected plates to be supported pivotally thereby on said posts, a shoe carried by said beam, and a locking-detent supported by the posts and arranged to engage with the rack, substantially as de- 45 scribed.

7. In an anchor for excavators, the combination with uprights or posts, of wear-plates fixed to the opposing faces of said posts, connected guide-plates pivoted to the posts and 50 lying within the wear-plates thereon, an anchor-beam provided with a rack and slidably fitted within the pivotal plates, a shoe carried by the beam, and a locking-bail hung on the posts for engagement with the rack and 55 provided with a weighted arm, substantially as described.

8. In an anchor for excavators, the combi-

nation with an upright or post, of a sectional jointed anchor-beam supported on said upright for slidable and pivotal movement thereon, a shoe carried by the outer end of said jointed beam, an elevating-cable connected with said beam near the joint between its members, and a haulage-cable connected to the joint between the members of said beam, 65 substantially as described.

9. In an anchor for excavators, the combination with an upright, of a sectional jointed anchor-beam, a guide-frame carried by said upright and slidably receiving the jointed anchor-beam, a shoe mounted on the anchor-beam, an elevating-cable guided by the frame and connected to the anchor-beam, and a haulage-cable connected with the sectional beam at the joint thereof, substantially as described. 75

10. In an anchor for excavators, the combination with an upright, of a guide-frame supported thereon, a jointed sectional anchor-beam slidably fitted to the upright and the guide-frame, an elevating-cable guided on 80 said frame and having a clevis which is connected with the anchor-beam, a haulage-cable connected to the joint of said sectional beam, and a shoe having a jointed connection with the outer end of the sectional beam, sub- 85 stantially as described.

11. In an anchor for excavators, the combination with an anchor-beam, of a shoe, a hinge-bar pivoted on said shoe, and a hinge-pintle lying at right angles to the hinge-bar 90 and connected to said beam and the bar, substantially as described.

12. In an anchor for excavators, the combination with an anchor-beam, of the hinge-plates fixed thereto, a shoe, a hinge-bar pivoted on the shoe and provided with hinge-plates, and a pintle or bolt lying at right angles to the hinge-bar and connecting the plates of the beam and said bar, substantially as de- 95 scribed.

13. In an anchor for excavators, the combination with uprights, an anchor-beam, and a shoe, of a universal joint between the shoe and beam, and braces connected to the uprights and to one of the hinge-bolts of the universal joint, substantially as described. 100

In testimony that I claim the foregoing as my own I have hereto affixed my signature in the presence of two witnesses.

HENRY C. LEHMAN.
